UNITED STATES PATENT OFFICE.

THOMAS E. DIMELOW, OF PHILADELPHIA, PENNSYLVANIA, ASSIGNOR TO JOHN W. MCKINNON, OF YORK, PENNSYLVANIA.

DENTAL FACING.

Application filed January 14, 1926. Serial No. 81,284.

The invention relates to improvements in artificial teeth of the general type shown by my U. S. Patents No. 947,378 and No. 1,070,785, in which a porcelain facing is provided in its lingual side with a socket to receive a projecting pin on a backing with which said lingual side contacts. Experience has taught that the pin has a tendency to split the facing, under the continual strain of mastication, as each thrust placed upon the facing causes tight forcing against the pin of the side of the socket or bore toward the occlusal end of said facing. It is the object of the present invention, therefore, to provide a new and improved construction in which all thrusts placed on the aforesaid socket side, are transmitted to the solid portions of the facing at opposite sides of the portion which is weakened by the socket.

With the foregoing in view, the invention resides in the novel subject matter herein-after described and claimed, the description being supplemented by the accompanying drawing.

Figure 1 is an inner side elevation of the improved facing and the backing, showing the strain transmitting means in dotted lines.

Figure 2 is a vertical sectional view as indicated by line 2-2 of Fig. 1.

Figure 3 is a view similar to Fig. 2 but illustrating a different form of construction.

Figure 4 is a sectional view as indicated by line 4-4 of Fig. 3.

Figure 5 is a perspective view of the form of reinforcing and strain transmitting member shown in Figs. 3 and 4.

Figure 6 is an edge view showing a still further form of reinforcing and strain transmitting member.

In the drawing above briefly described, the numeral 7 designates a backing plate whose outer side is provided with at least one rigidly attached projecting pin, a plurality of these pins being preferably employed, as indicated by the numerals 8.

These pins, as in the patents above referred to, converge with the backing 7 in a direction away from the occlusal edge of the latter and while this construction is preferable, it is possible that good results could be obtained with other angular relations of backing and pin or pins.

The numeral 9 designates the artificial

tooth or facing, whose lingual side is intended to contact with the buccal side of the backing 7, said facing having a socket or bore 10 for each pin 8, the pin or pins being suitably cemented in the socket or sockets. 60 By preference, each pin is formed near its free end, with a peripheral groove 11 to permit more effective anchoring by the cement.

When an artificial tooth of the type above described, is in use, each thrust placed upon the tooth or facing 9, during a process of mastication, causes the side of the socket or bore 10, toward the occlusal end of the facing, to thrust forcibly against the pin 8, the result being that there is quite a forcible 70 tendency to split the facing. To overcome this difficulty, I have provided the improvement now to be described.

The form of construction shown in Figs. 1 and 2 will be first explained. In these views, 12 designates an elongated reinforcing and strain-transmitting member whose intermediate portion 13 is positioned between the socket or bore 10 and the occlusal end of the facing 9, said intermediate portion 80 being exposed at the interior of said socket or bore, at the side of the latter toward said occlusal end. The end portions or arms of the member 12 extend in substantially a labio-gingival direction from 85 the socket or bore 10, diverge toward the vertical edges of the facing, and are embedded in the solid portions of the tooth or facing, at opposite sides of the central portion, which is weakened by said socket or bore. Each thrust upon the facing, is received by the intermediate portion 13 of the member 12, and by this member is transmitted to solid portions of the facing which are well capable of withstanding the strain 90 and thus the danger of splitting the facing is effectively overcome.

The member 12 is by preference of substantially U-shape and it may be formed with openings 14 or may be otherwise constructed to permit effective anchorage in the facing or tooth. While this member is preferably embedded in the facing by molding the latter around it, it is possible to secure said member within a cavity of the 105 facing by the use of some molten metal.

In the form of construction shown in Figs. 3, 4 and 5, the construction is analogous to that above described. The member 12 however is a slightly different shape and 110

its intermediate portion 13^a is in the form of a sleeve-like lining for the socket or bore of the facing. The lining 13^a may be of any desired length, from a mere ring to quite an elongated tube and it may either be continuous circumferentially, or may be split. In Fig. 6, a lining portion 13^b is shown on a reinforcing and strain-transmitting member 12^b, said lining portion being 10 split.

It will be seen from the foregoing that a distinct improvement has been produced, over the subject matter shown by the prior art, and it will be understood that I am not 15 restricted to exact details which I have selected for illustration in the present application.

It may be added, that when a sleeve or the like is provided at the intermediate portion of the reinforcing and strain-transmitting member, it serves effectively to hold 20 said member in proper place while the porcelain facing is being molded around it. This construction has also been found to be 25 of advantage in properly locating and spacing the sockets of the facing, so that a backing prepared for use with any facing, is also usable with any other facing. Obviously, the invention may be used in 30 connection with an artificial tooth of any de-

sired size and shape, to replace any natural tooth in the dental arch.

I claim:

1. An improvement in a dental facing of the type whose lingual side is adapted to contact with a backing; said facing being formed with a bore which extends labio-occlusally from said lingual side and is open at its lingual end only to receive a backing-carried pin; said improvement comprising a relatively long and narrow U-shaped metal strip which is embedded in the facing in a plane at substantially right angles to the axis of said bore, the intermediate portion of said U-shaped strip being disposed at the side of the bore toward the occlusal end of the facing while the arms of said strip extend from the bore in substantially a labio-gingival direction but also diverge to points near the vertical edges of the facing.

2. A structure as specified in claim 1; together with a metal sleeve connected to and extending transversely of said intermediate portion of the U-shaped strip, said sleeve being co-axial with and forming a lining for said bore.

In testimony whereof I have hereunto affixed my signature.

THOMAS E. DIMELOW.
